CLAIM

The ornamental design for an internet voice gateway, as shown and described.

DESCRIPTION

FIG. 1 is a top, front, right side perspective view of an internet voice gateway showing my new design;

FIG. 2 is a front side elevational view thereof;

FIG. 3 is a rear side elevational view thereof;
FIG. 4 is a left side elevational view thereof;
FIG. 5 is a right side elevational view thereof;
FIG. 6 is a top plan view thereof; and,

FIG. 7 is a bottom plan view thereof.
